UNITED STATES PATENT OFFICE.

WILLIAM E. WINE, OF TOLEDO, OHIO.

DOOR DEVICE.

Original application filed January 12, 1922, Serial No. 528,651, now Patent No. 1,455,694, dated May 15, 1923. Divided and this application filed October 31, 1922. Serial No. 598,095.

This invention relates to new and useful improvements in car door devices and is a division of my application filed on January 12, 1922, entitled car door locking devices, 5 and bearing Serial No. 528,651 now Patent 1,455,694 of May 5, 1923.

One of the objects of the present invention is to provide a car door with an economical form and arrangement of supporting arms affording a very sturdy construction wherein the material will be utilized to obtain the maximum results with the least expenditure of metal.

Another object of the present invention is 15 to provide a construction for drop bottom doors of freight cars which will not only brace the doors, but, at the same time, will provide a means whereby the doors may be well supported and firmly held in closed 20 position.

A further object of the present invention is to provide supporting arms which are attached to the under surface of the door and are offset near their outer ends, at which 25 points strengthening members in the form of brackets are inserted. To avoid undesirable weakening of the car structure it is necessary that these arms be offset as they must extend outwardly beyond the side sill 30 of the car so that they may be readily engaged by hooks or other forms of supporting and locking mechanisms.

Still another object of the invention is to provide supporting arms which may be 35 formed of conventional angle irons arranged with their upper legs extending in opposite directions to form seats respectively adapted to be engaged by the supporting hooks or other devices which are used for this purpose.

With these and other objects in view, the invention consists in certain novel arrangements and combinations of parts as will be hereinafter more fully described and pointed out in the claims.

Referring now to the drawings showing a preferred embodiment of my invention—

Figure 1 is a diagrammatic view of a freight car showing the supporting arms 50 and the hooks engaging the same as applied to two of the doors.

Figure 2 is a view in elevation of a fragmentary portion of a car side showing the relative position of the supporting arms and

the hooks when the doors are in closed position.

Figure 3 is a detail sectional view taken on line 3—3 of Fig. 2 looking in the direction of the arrows.

Figure 4 is a fragmentary view showing a portion of the door and a supporting arm, the door being supported in a temporary or partly closed position.

Figure 5 is a fragmentary sectional view taken on line 5—5 of Fig. 4 and showing a lever in position for forcing the door to a closed position.

The drawings show the side of a car 1, having the usual uprights or braces 2, a side sill 3, a portion 4 of the floor and a door 5. 70 In the present embodiment of the invention it will be noticed that the floor is cut away as at 6 and the door 5 is located beneath said opening and beneath the level of the floor.

Riveted to the center sill 7 of the car is a bracket 8 to which the door is hinged, a leg of the hinge being preferably secured to the door 5 through one end of the supporting arm 9 which will be described later more 80 in detail.

It is to be understood that preferably there will be two supporting arms for each door and naturally two brackets and sets of hinges.

These supporting arms 9 are preferably formed of angle iron and are bolted to the bottom of the door. They preferably extend from the rear or hinged edge of the door nearly to the free edge thereof remote 90 from the hinges, and at their outer ends are provided with extensions or short arms 10 which are preferably somewhat heavier per foot than the arms 9. The corresponding arms 9 and 10 are rigidly connected, preferably by means of rivets as shown. The extensions 10 are offset with respect to the major portions of the arms 9 and extend outwardly parallel with the door, as clearly shown at 11 in Fig. 3, their length being 100 such that they project beyond the free edge of the door and beyond the outer plane of the side sill 3, thus providing ledges for hooks 12 or other suitable locking mechanisms which may be mounted upon the side 105 of the car for cooperation therewith. The portions of the arms 9 and 10 through which the parallel portions of said arms are con-

nected preferably slope or incline downwardly and outwardly from the plane of the door.

Extending transversely of the door and secured to the bottom or outer face thereof near the free edge remote from the hinges is a stiffening beam or reinforcing member which is preferably in the form of the channel 14, the lower leg of said channel being in contact with and riveted to the respective top legs or flanges of the short arms 10, its upper leg being rigidly connected to the door, and its intermediate portion constituting a stiffening web extending outwardly from the outer face of the door. The channel 14, it will be perceived, serves as a reinforcing member for the free edge of the door and, as will hereinafter appear, provides a seat spaced from the outer face of the door for cooperating with the inner end of a removable lever 18 for forcing the door to closed position. The channel 14 also acts to space the door arms 10 as well as to afford seats or abutments for receiving the reactions of the outer ends of the arms 10 when the latter are engaged with the hooks 12 to hold the door in closed position.

Securely riveted to the inner surface of the channel 14 and to the respective arms 9 and 10 is a triangular bracket or gusset 16 which occupies the space defined by portions of the arms 9 and 10, the bottom or outer face of the door 5 and the inner wall of the said channel. A bracket is provided for each of the arms 10, thus bracing the door near its opposite sides and also bracing the supporting arms 9 and 10. It is to be understood that it is preferable to employ arms 9 with short arms 10 riveted thereto, although, of course, two long continuous arms offset as shown might be used if desired.

The construction described provides an economical and rigid structure as the supporting arms not only afford conveniently located ledges for cooperating with locking members movably mounted on the side of the car, but are rigidly held and strengthened by the employment of the brackets 16 and the channel 14.

The lower edge of the side of the car which is embodied in the channel 3 lies below the plane of the car floor 4 and below the plane of the door 5. As the door-supporting hooks 12 which are movably mounted upon a stationary part of the car are preferably pivoted upon the side sill 3, the outer ends 11 of the door arms 10 are spaced away from the bottom or outer face of the door so that they may extend outwardly beneath the side sill of the car to a point beyond the outer plane thereof enabling them to engage the shoulders or ledges of the hooks. It is desirable in such a construction that the spaced ends of these arms 10 should be stiffened and tied to the door in a man-

ner which will brace them against movement, either lengthwise of the door or crosswise thereof. The braces or gussets 16 and the reinforcing channel member 14 effectively fulfill these purposes. The triangular gussets 16 stiffen the arms and brace them crosswise of the door and also serve to stiffen and brace the channel 14, while the latter in turn holds the braces in their positions at right angles to the free edge of the door and braces the outer ends of the arms 10 against movement lengthwise of the door. It will thus be seen that these several members support and brace each other so as to strengthen the door and maintain all parts in their correct positions. It will also be appreciated that by arranging the door arm to seat beneath the spacing and reinforcing channel member 14 between the extremities of the arm, and by securing the inner extremity of the arm to the door, as for example by means of the gusset 16, the reinforcing arm member 9 and the rivets used therewith, the metal of the door arm is utilized to the best advantage and the stress therein incident to supporting the loaded door at the outer end of the arm will be minimized.

The hook 12 preferably seats beneath one leg only of the angle iron and the weight of the loaded door therefore is transmitted to the hook through this leg alone. In order that both legs of this angle iron arm 10 may be utilized for resistance at the point of greatest stress in the arm, it is preferable that both legs of the angle should be suitably secured to the door. For this purpose a rivet is employed for attaching the horizontal leg of this angle to the bottom flange of the channel 14, which latter is in turn secured to the door by means of bolts, while other rivets firmly connect the vertical leg of this angle to the gusset 16 which is secured to the door and also to the channel 14.

By positioning the side sill channel 3 with its flanges extending inwardly the hook 12 may be arranged close to the plane of the outer face or side wall of the car, thus reducing the over-all width of the car and providing a construction that is unlikely to become inoperative through bending or warping of parts. The hook engaging flanges or legs of the supporting arms 10 of each door preferably extend in opposite directions from the vertical legs of the said arms, so that when they are engaged by the oppositely facing hooks 12 or other preferable supporting means any tendency of the door to shift longitudinally of the car will be overcome; but this latter feature is the subject of another one of my pending applications.

A recessed fulcrum member, which may advantageously be formed as an apertured plate 17, is preferably fastened to the car side midway between the supporting arms 10

10. By passing a removable lever, such as 18, through the aperture in the plate the inner end of said lever may be caused to seat against the lower part or flange of the 5 channel 14 adjacent either of the arms 10, thus enabling the door to be readily forced to a closed position. This fulcrum construction in its broad aspect forms the subject matter of the original application of which 10 this is a division.

From the foregoing it will be perceived that I have provided a construction whereby the door is greatly strengthened and braced throughout and by which convenient means 15 are provided for constituting ledges suitable for engagement by any desirable form of door supporting and locking mechanism mounted on the side of the car.

Many slight changes might be made in 20 the construction without departing from the spirit and scope of my invention.

I claim:

1. In a door device for railway cars, the combination with a car having a floor and 25 a side, the lower edge of the latter being disposed below the line of the floor, of a door hinged to the car body and lying above the bottom of the car side, supporting arms affixed to the door and extending downwardly near their forward ends and then outwardly beneath and beyond the car side to form supporting ledge, a strengthening 30 member secured to said arms and to said door near the free edge thereof, and means 35 adapted to engage said ledges to hold the door in its closed position.

2. In a door device for railway cars, the combination with a car having a floor and a side, the lower edge of the latter disposed 40 below the line of the floor, of a door hinged to the car body and lying above the bottom of the car side, supporting arms affixed to the door and extending downwardly near their forward ends and then outwardly beneath and beyond the car side to form supporting 45 ledges, a strengthening member secured to the door and to said arms, brackets interposed between the strengthening member, the car door and said arms, 50 and means secured to the car body for engaging said ledges.

3. In a door device for railway cars, the combination with a car having a floor and a side with the lower edge of the latter disposed 55 below the line of the floor, of a door hinged to the car body and lying above the bottom of the car side, supporting arms affixed to the door and extending downwardly at their forward ends, short arms 60 secured to said supporting arms, the said short arms being offset and extending outwardly beneath the bottom of the car side to form ledges, and means mounted on the car side for engaging said ledges to support 65 said door.

4. In a door device for railway cars, the combination with a car having a floor, and a side sill extending below the line of the floor, of supporting arms secured to the under surface of the door, and extending 70 downwardly from the door at their forward ends, short arms respectively secured to said supporting arms, said short arms being bent downwardly and outwardly to form retaining ledges extending beyond the car side, 75 and means cooperating with said ledges to support said door in closed position.

5. In a door device for railway cars, the combination with a car having a floor and a side, the lower edge of the latter disposed 80 below the line of the floor, of a door hinged to the car body and lying above the bottom of the car side, supporting arms affixed to the door and extending downwardly near their forward ends, short arms respectively 85 secured at the forward ends of said supporting arms, each of said short arms extending downwardly and outwardly beneath and beyond the lower edge of the car side, a channel member secured to the bottom of the 90 car door and to said short arms, brackets interposed between the car door, the channel member, and the adjacent ends of the supporting arms and the short arms, and means cooperable with the side of the car 95 for engaging the outer portion of the short arms to support said door in closed position.

6. In a door device for railway cars, the combination with a car having a floor and a side, the lower edge of the latter being disposed below the line of the floor, of a door hinged to the car body and lying above the bottom of the car side, supporting arms affixed to the door, short arms respectively 100 secured to the forward ends of said supporting arms, the short arms being of heavier metal per foot than the supporting arms and extending outwardly beyond the car side in a plane lower than that of the plane of the supporting arms, a strengthening 110 member interposed between the car door and the short arms and secured thereto, brackets interposed between the car door and the strengthening member and secured to the supporting arms, the forward ends of the 115 short arms forming ledges, and means attached to the car side for engaging said ledges to retain said door in closed position.

7. In a door device for railway cars, the combination with a car having a floor and a side, the lower edge of the latter being disposed below the line of the floor, of a door hinged to the car body and lying above the bottom of the car side, supporting arms affixed to the door, a short arm of metal 120 relatively heavier per foot than said supporting arms secured to the forward end of each of said supporting arms and extending outwardly beyond the car side in a plane 125 lower than that of the plane of the door, said 130

short arms forming ledges which are disposed in opposite directions, portions of said short arms extending in a plane parallel with the car door, a strengthening member inserted between said portions of said arms and the car door, and plates respectively interposed between the car door, the strengthening member and a portion of each of the short arms for bracing said door said supporting arms being adapted through said ledges to be supported from means associated with the car side.

8. In a door device for railway cars, the combination with a car having a floor and a side with the lower edge of the same disposed below the line of the floor, of a door hinged to the car floor and lying above the bottom of the car side, a spacing member affixed to the door and extending downward approximately to the line of the bottom edge of the car side, a door-supporting arm affixed to the door and seated upon the said spacing member, the said arm extending outward beneath the bottom of the car side, and means secured to the car side and arranged for cooperation with the end of the said arm for retaining the door in closed position.

9. In a door device for railway cars, the combination with a car having a floor and a side with the lower edge of the same below the line of the floor, of a door hinged to the car floor and lying above the bottom of the car side, a spacing member affixed to the door near the edge thereof and extending downward from the door approximately to the plane of the bottom edge of the car side, a bracing member secured to the door and having its end bent away from the door towards the lower end of the spacing member, a door supporting arm secured at its inner end to the said spacing member and extending at its outer end beneath the bottom edge of the car side to a point outside the plane of the car side and seating between its extremities upon the said spacing member, and means operatively interposed between the car side and the end of the said arm for holding the door in closed position.

10. In a door device for railway cars, the combination with a car having a floor, and a side sill extending below the line of the floor, of an arm carried upon the lower face of the door and extending downwardly therefrom approximately to the line of the lower edge of the said side sill, a bracket near the end of the said arm, the same constituting securing means between the door and said arm, and means depending below the said side sill and adapted to cooperate with the said arm for securing the door in closed position.

11. In a door device for railway cars, the combination with the door, of an angle iron affixed thereto and extending outwardly slightly beyond one edge of the door, a

door-securing member pivoted upon the car and arranged for supporting engagement with one leg only of the said angle iron, and means for attaching the angle iron to the door, the said means involving a plurality of securing devices respectively passing through both legs of the angle iron and through adjacent parts of the door, to thereby stiffen the angle iron adjacent the point of the engagement therewith of the door-securing member.

12. In a door device for railway cars, the combination with a car having a floor, and a side still extending below said floor, of a swinging door having a spacing member affixed thereto, said spacing member being located near the free edge of the door and extending downwardly from the door, an arm affixed to the door and extending outwardly beyond an edge of the door, and door-supporting means operably interposed between the car body and the outer end of the said arm, the said arm being seated beneath the said spacing member, the door-supporting means being engageable with the said arm outside of the point of contact of the latter with the spacing member, and the arm being affixed to the door at the opposite side of said point of contact.

13. In a door device for railway cars, the combination with a car having a longitudinally extending center sill, and a longitudinally extending flanged side sill disposed with one flange thereof turned inwardly toward the center of the car, of a door in the floor of the car, the same being hinged along the center sill, the free edge of the door being arranged to lie, when closed, slightly inside of and along the inner edge of the inturned flange of the side sill, and door-supporting means carried by the side sill upon the outer face thereof, the same being arranged to swing at right angles to the swing of the door, into and out of supporting engagement with the said door.

14. In a door device for railway cars, the combination with a car having a longitudinally extending center sill and a longitudinally extending flanged side sill disposed with one flange thereof turned inwardly toward the center of the car, of a door in the floor of the car, the same being hinged along the center sill, the free edge of the door being arranged to lie, when closed, slightly inside of and along the inner edge of the inturned flange of the side sill, angle iron reinforcements secured to the lower face of the door, the same having extensions projecting outwardly beyond the plane of the side of the car, and door-securing hooks pivoted upon the outer face of the said side sill, the same being arranged to swing at right angles to the swing of the door into and out of supporting engagement with the ends of the said reinforcement angles.

15. In a door device for railway cars, the combination with a door, of a member affixed to said door and extending outwardly therefrom slightly beyond one edge thereof, a door supporting means operably associated with said member, the said member being formed of a section having flanges disposed at right angles to each other, one of said flanges forming a seat for said door supporting means, and a plurality of means respectively passing through said flanges for securing said member to said door. 70
16. In a door device for railway cars, the combination with a hinged door, of a member secured to said door and projecting outwardly beyond an edge thereof, means for attaching said member to said door, and means cooperating with said member for supporting said door in closed position, said member having a cross sectional form involving plate-like portions extending at an angle to each other, the said means for attaching said member to said door involving a plurality of securing devices respectively extending through a plurality of said plate-like portions one of which forms a seat adapted to be engaged by said means for supporting the door in closed position. 80
17. In a door device for railway cars, the combination with a car having a floor, and a side sill extending below said floor, of a swinging door, means for supporting said door in closed position, said means involving a flanged member rigidly connected to said door and projecting outwardly from beneath an edge thereof, means movably mounted on a stationary part of the car adapted to engage said flanged member to maintain said door in closed position, and means interposed between said door and said flanged member for spacing the latter away from the under side of said door. 90
18. In a door device for railway cars, the combination with a hinged door, of means for supporting said door involving a flanged member rigidly connected to said door and having a plurality of angularly disposed flanges projecting outwardly from beneath an edge thereof, one of said flanges being disposed in a plane substantially normal to the hinge axis of the door, means movably mounted on a stationary part of the car for engaging one of said angularly disposed flanges to maintain said door in closed position, and means for connecting said flange member to said door, said movably mounted means being adapted to engage one of the outwardly projecting flanges of said flanged member to thereby support said door, the said connecting means including means extending through the portion of said flanged member disposed in a plane substantially normal to the hinge axis of the door. 100
19. In a door device for railway cars, the combination with a swinging door, of means for supporting said door in closed position, said means involving a flanged member having a portion extending substantially parallel to the plane of said door and a portion extending substantially perpendicular thereto, means projecting from the plane of said door and extending substantially parallel to its axis of swinging movement for stiffening said door, means movably mounted on a stationary part of the car for releasably engaging a portion of the flanged member which is parallel to the plane of the door to maintain said door in closed position, and means for connecting said flanged member to said stiffening means, the latter being disposed between said flanged member and said door and having at its lower edge a flange extending substantially parallel to the plane of said door and engagingly overlapping said flanged member. 110
20. In a door device for railway cars, the combination with a swinging door, of a door reinforcing member affixed to said door and terminating adjacent an edge thereof, an arm forming an extension of said reinforcing member and projecting beyond the end of the latter and beyond said adjacent edge of the door, and means operatively interposed between said arm and a stationary part of the car for releasably supporting said door in closed position, said arm and said reinforcing member being rigidly connected to said door, and said arm beyond said edge of the door having a cross-sectional area greater than that of said reinforcing member. 120
21. In a door device for railway cars, the combination with a swinging door, of means affixed to the under side of said door for reinforcing the same, said means including a portion overlapping said door and a portion projecting beyond an edge of said door, said door overlapping portion being of less cross-sectional area than said projecting portion, and means movably mounted on a stationary part of the car for releasably engaging said projecting portion to support said door in closed position. 130
22. In a door device for railway cars, the combination with a swinging door, of means for supporting said door in closed position, said means involving a plurality of spaced members projecting outwardly beyond one of the edges of said door, a plurality of means operatively interposed respectively between said spaced members and a stationary part of the car, and flanged means extending between and secured to said spaced members intermediate the ends of the latter for maintaining said members in spaced relation and to afford abutments for receiving the reactions of the members when the door is supported in closed position. 140
23. In a door device for railway cars, the combination with a swinging door, of a plu- 150

- rality of spaced members extending beyond an edge of said door, a plurality of hooks respectively cooperating with and adapted to be disengaged from said spaced members and operatively interposed between said spaced members and a stationary part of the car, and means secured to said door and to said spaced members for maintaining the latter in spaced relation.
- 10 24. In a door device for railway cars, the combination with a swinging door, of a plurality of spaced members extending outwardly in the same direction beyond an edge of said door, the outer ends of said members being bent downwardly away from the door, a plurality of means carried by the car and respectively cooperating with said spaced members for releasably supporting said door in closed position, and means affixed to said door and extending between and secured to the downwardly bent portions of said members for maintaining the latter in spaced relation.
- 15 25. In a door device for railway cars, the combination with a swinging door, of a plurality of flanged members spaced with relation to each other along an edge of said door and projecting outwardly from said edge in the same direction, a plurality of oppositely facing hooks movably mounted on a stationary part of the car and respectively adapted to engage said flanged members to support said door in closed position, and flanged means extending between and secured to said flanged members for maintaining the latter in spaced relation.
- 20 26. In a door device for railway cars, the combination with a hinged door, of a plurality of arms movable with and extending outwardly from beneath said door, a flanged member secured to the under side of said door along the edge thereof opposite the hinge, said flanged member extending between and being rigidly secured to said arms, and a plurality of hooks movably mounted on a stationary part of the car for respectively engaging said arms to support said door in closed position.
- 25 27. In a door device for railway cars, the combination with a hinged door, of a plurality of arms connected to and extending outwardly from beneath said door, a plurality of hooks operatively interposed between the respective arms and a stationary part of the car for releasably supporting said door in closed position, a flanged member secured to the under side of said door along the edge thereof opposite the hinge and extending between and rigidly connected to said arms, and fulcrum means for cooperating with a removable lever adapted to engage said flanged member to force said door to closed position.
- 30 28. In a door device for railway cars, the combination with a hinged door, of a plurality of flanged arms movable with and projecting outwardly from said door, a flanged member secured to said door along the edge thereof opposite the hinge and rigidly connected to said arms, a plurality of oppositely facing hooks movably mounted on a stationary part of the car and respectively adapted to engage said flanged arms to support said door in closed position, and fulcrum means for cooperating with a removable lever adapted to engage said flanged member to force said door to closed position.
- 35 29. In a door device for railway cars, the combination with a hinged door, of a plurality of arms movable with and projecting outwardly from said door, a door reinforcing member secured to said door along the edge thereof opposite the hinge, a plurality of hooks movably mounted on a stationary part of the car and respectively adapted to engage said arms to support said door in closed position, and fulcrum means for cooperating with a removable lever adapted to engage said door reinforcing member to force said door to closed position.
- 40 30. In a door device for railway cars, the combination with a hinged door, of a plurality of arms movable with and projecting outwardly from said door, a plurality of hooks movably mounted on a stationary part of the car and respectively adapted to engage said arms to support said door in closed position, means rigidly secured to said door constituting a lever seat spaced downwardly from the plane of said door, and fulcrum means for cooperating with a removable lever adapted to engage said lever seat to force said door to closed position.
- 45 31. In a door device for railway cars, the combination with a swinging door, of a pair of spaced hinges for movably connecting said door to the car body, a pair of flanged members extending from said hinges toward and beyond the free edge of the door remote from said hinges and projecting beyond a side wall of the car, pivotally mounted door supporting members carried by the said side wall of the car and respectively adapted to cooperate with the adjacent ends of said flanged members to support said doors, and stiffening means bordering and extending parallel to the free edge of the door remote from the hinges thereof, said stiffening means embodying a web of metal outstanding from the outer face of the door, and the said flanged members being arranged to react against said stiffening means inwardly of their outer ends.
- 50 32. In a door device for railway cars, the combination with a door hinged to the car body, of a pair of spaced stiffening members extending from the hinged edge of the door and terminating at their outer ends beyond the free edge of said door remote from said hinged edge, door supporting members piv-

- totally mounted upon a wall of the car for respectively engaging the outer ends of said stiffening members to support said door in closed position, a beam secured to the door 5 and extending along said free edge thereof, said stiffening members being seated against said beam inwardly of their outer ends, and means adapted to cooperate with a removable door closing member for forcing said 10 door to closed position, said means comprising a member which is recessed to accommodate said removable member and is positioned to permit said removable member to engage the said beam at a point between said 15 stiffening members.
33. In a door device for railway cars, the combination with a door hinged to the car body, of stiffening means extending along one of the edges of said door and involving 20 a web outstanding from the outer face of said door, and a flange extending at an angle to said web in spaced relation to said door, an arm secured to the door and extending outwardly beyond the said edge thereof, and 25 a member pivoted upon the car and adapted to cooperate with said arm for supporting said door, the said flange constituting a seat for the said arm.
34. In a door device for railway cars, the combination with a door hinged to the car 30 body, of an arm secured to said door and extending outwardly beyond an edge thereof, a beam secured to said door along the said edge, said beam having a flange lying 35 against and secured to the outer face of the door and having a web outstanding from said face and having an outer flange extending at an angle to said web and forming a seat for said arm spaced from said first 40 named flange, and means movably mounted upon the car and adapted to releasably engage the said arm outwardly of its point of seating on said flange.
35. In a door device for railway cars, the combination with a door hinged to the car 45 body, of a pair of spaced arms extending outwardly beyond the free edge of said door remote from the hinged edge thereof, a beam carried by said door at the free edge thereof 50 and extending parallel therewith, said beam having a flange contacting said door and another flange extending parallel to said door in spaced relation thereto, the said last named flange providing seats for the said 55 arms, and means carried by the car body for respectively engaging said arms to support said door.
36. In a door device for railway cars, the combination with a door hinged to the car 60 body, of a reinforcing member for said door outstanding from the outer face thereof along one of its edges, an angle iron secured to said door inwardly of said edge and extending under said reinforcing member and 65 projecting beyond said edge, and a pivoted member carried by the car body for engaging said angle iron to maintain said door in closed position, the inner end of said angle iron lying against said door and the outer end thereof being spaced downwardly 70 away from the door in a plane substantially parallel thereto to pass under said reinforcing member for engagement with said pivoted member.
37. In a dump car having a floor, a side 75 wall and a side sill extending below the level of the floor, the combination with a floor door pivoted to swing about an axis parallel with said side sill and having its free edge disposed adjacent the inner plane of 80 said side wall when said door is in closed position, of an arm secured to the under side of said door and extending downwardly adjacent said free edge thereof and outwardly to a point below said side sill and 85 beyond the outer plane of the latter, and means located outwardly of the outer plane of said side sill for cooperating with said arm to hold the door in closed position.
38. In a dump car having a floor, side 90 wall, and side sill depending below the level of the floor, the combination with a floor door pivoted to swing about an axis parallel with the side sill, of an arm of angular cross-section with the flanges thereof perpendicular to each other and extending from end to end of said arm, one of said flanges being secured to the under side of the door and said arm being bent downwardly and outwardly from the free edge of said door, and 95 means cooperable with the outer end portion of said arm to hold the door in closed position.
39. In a dump car having a floor and a side, the combination of a pivoted floor door, 105 of an arm of angular cross section arranged in overlapping relation to the door and extending from adjacent one edge thereof to a point outwardly of the opposite edge, said arm having offset portions, one for attachment to the door, the other for cooperation with means adapted to support the door in closed position, said portions being connected by a portion respectively forming an angle with each of said first named portions, and 110 a plate-like member for securing said connecting portion to the underside of the door.
40. In a dump car having a floor and a side, the combination of a pivoted floor door, 120 of an arm of angular cross section arranged in overlapping relation to the door and extending from adjacent one edge thereof to a point outwardly of the opposite edge, said arm having a portion secured to the door and having a portion cooperable with means for supporting the door in closed position, said portions being offset and connected by a relatively inclined portion, and means depending from said door for connecting said 125 inclined portions to the latter.

41. In a dump car having a floor and a side, the combination of a pivoted floor door, of an arm of angular cross section secured to the underside of the door, said arm being 5 bent downwardly adjacent one of its ends inwardly of the adjacent edge of the door and extending outwardly beyond the side of the car, and means mounted on the car side movable transversely of the arm into engagement with the outwardly extending end thereof for supporting the door in closed position.

42. In a railway dump car, the combination of a pivoted door, of a reinforcing framework secured to the underside of the door comprising a plurality of spaced members arranged substantially normal to the hinge axis of the door, and a member substantially normal to and rigidly connected 10 with said spaced members adjacent the edge of the door remote from the hinge axis thereof, the outer ends of said spaced members being bent downwardly to pass beneath the other of said members, the latter having a 15 flange parallel with and offset from the door affording means to which the outer ends of said spaced members are secured and means respectively cooperable with said spaced members for maintaining the door in closed 20 position.

43. A railway dump car having a floor provided with a lading discharge opening and having a side extending below the general level of the floor, a gravity actuated 25 door for closing said opening, means for supporting the door in closed position involving a pivoted hook carried by the car body and an arm carried by the door, the said arm being bent downwardly away from 30 the door to pass beneath the car side for operating with the pivoted hook, and a substantially triangularly shaped gusset for bracing the downwardly bent portion of the door arm.

44. A dump door for railway cars comprising a series of planks, a plurality of stiffening members extending transversely of said planks, the outer ends of said members being spaced downwardly from the latter to extend beneath the side of a car for cooperating with door supporting means, and substantially triangularly shaped gussets connecting the downwardly spaced portions of the stiffening members of the planks.

45. A dump door for railway cars comprising a series of planks, a plurality of

arms extending transversely of said planks, the outer end of each of said arms being bent downwardly away from the planks so as to extend beneath the adjacent side of a car for cooperating with door supporting means, and bracing means disposed longitudinally of each of the arms for respectively securing the downwardly extending portions of said arms to the planks. 60

46. A rigid frame for a composite dump door of the type involving a plurality of planks, said frame comprising a plurality of members, two of said members being arranged in a position substantially normal 70 to each other, and one of said members having a portion rigid therewith adapted to extend outwardly beyond an edge of the door for cooperation with means for maintaining the door in closed position.

47. A rigid frame for a composite dump door of the type involving a series of planks, said frame comprising beam members extending transversely of the planks and a beam member extending longitudinally of 80 the planks adjacent the outer edge of the door, said transversely extending members projecting outwardly of the outer edge of the door for cooperation with means for maintaining the door in closed position.

48. A rigid frame for a composite dump door of the type involving a series of planks extending longitudinally of the car, said frame comprising members extending transversely of the planks and a member extending substantially longitudinally thereof in parallelism with the free edge of the door, and hinge straps respectively rigidly connected to said transversely extending members. 90

49. A rigid frame for a composite dump door of the type involving a series of planks extending longitudinally of the car, said frame comprising a plurality of members extending transversely of the planks and a member extending longitudinally thereof adjacent the free edge of the door, door arms rigidly secured to the transversely extending members adjacent the free edge of the door and projecting outwardly therebeyond, and 100 hinged straps rigidly connected to the opposite ends of said transversely extending members.

In testimony whereof I affix my signature.

WILLIAM E. WINE.
